UNITED STATES PATENT OFFICE.

DANIEL SCOTT, OF BROOKLYN, NEW YORK, ASSIGNOR TO HIMSELF AND
HENRY C. BECKER, OF SAME PLACE.

CHIMNEY OR VENTILATOR CAP.

SPECIFICATION forming part of Letters Patent No. 424,135, dated March 25, 1890.

Application filed November 5, 1889. Serial No. 329,324. (Model.)

To all whom it may concern:

Be it known that I, DANIEL SCOTT, of Brooklyn, in the county of Kings and State of New York, have invented a certain new and useful 5 Improvement in Chimney or Ventilator Caps or Cowls, of which the following is a specification.

My improvement relates to caps or cowls which are to be placed upon the upper end of 10 ventilator shafts or chimneys; and the object of the improvement is to induce a draft up the ventilator shaft or chimney irrespective of the direction in which the wind may be blowing and as a consequence to preventing 15 the wind from passing down the chimney or ventilator.

I will describe in detail a chimney or ventilator cap or cowl embodying my improvement, and then point out the novel features 20 in a claim.

In the accompanying drawings, Figure 1 is an elevation of a chimney cap or cowl embodying my improvement and showing a portion 25 of a chimney or flue upon which the same is arranged. Fig. 2 is a vertical section of the same.

Similar letters of reference designate corresponding parts in both the figures.

A designates a chimney or flue. This chimney or flue may be of any desired shape, but 30 I have illustrated it as cylindrical.

This cap or cowl is composed of a downwardly and inwardly extending portion a in the form of an inverted frustum of a cone. 35 To the upper edge portion of the part a is secured an upwardly and inwardly extending portion a' , forming the frustum of a cone. Surrounding the portion a' and either secured thereto or made integral therewith is an outwardly-flaring portion a^2 . The cap or cowl 40 is supported from the portion a by means of supporting-pieces a^3 , secured near their upper ends to the lower edge portion of the portion a and at their lower ends to a sleeve a^4 , which sleeve is adapted to be passed over the upper end portion of the chimney or flue A. I have shown a ring a^5 , surrounding the sleeve a^4 , near the lower part of the latter. Between 45 said ring a^5 and the sleeve a^4 the lower ends of the supporting-pieces a^3 are secured. They may thus be secured by solder, rivets, or otherwise.

It will be observed that the supporting-pieces a^3 maintain the portion a of the cap or cowl at a considerable distance from the chimney or flue, so that there will be a space a^6 between said chimney or flue and the portion a , through which the wind may freely blow irrespective of the direction from which it may come.

Surrounding the cap or cowl, and maintained at a considerable distance above the same, is a deflector B. This deflector has a closed bottom or under side and is supported over the portion a^2 , in the cap or cowl, by means 65 of supporting-pieces b , which supporting-pieces are secured near one of their ends to the portion a^2 and near their other ends to the deflector B. The deflector B is maintained at a height above the cap or cowl, so 70 that a clear space for the circulation of the wind will be afforded between the upper end of the cap or cowl and the deflector.

It is to be observed that the space inclosed by the portion a' of the cap or cowl above 75 the chimney is wholly free and unobstructed.

The construction of this cap or cowl is such that no matter in what direction the wind may be blowing an upward draft will be caused through the chimney or flue and no 80 wind can blow down the same.

What I claim as my invention, and desire to secure by Letters Patent, is—

The combination, with a sleeve adapted to be passed downwardly about the upper end 85 of a chimney or flue, of a cap or cowl consisting of a downwardly and inwardly extending portion a , supported from said sleeve so that a space will be left between it and the sleeve upon all sides, an upwardly and inwardly extending portion a' , supported by the portion a , an outwardly-flaring portion a^2 upon the upper end of the portion a' , and a deflector having a closed bottom supported 90 upon said portion a^2 , so that an open space 95 will be left between said deflector and the portion a^2 , the space inclosed by the portion a' above said sleeve being wholly unobstructed, substantially as specified.

DANIEL SCOTT.
